195,908

CAMERA FOR USE WITH CHECK CASHING OPERATION

David Sigmond, 13-11 Brightwater Ave., Brooklyn, N.Y.

Filed Nov. 24, 1961, Ser. No. 67,683

Term of patent 14 years

(Cl. D61-1)

I claim:

The ornamental design for a camera for use with check cashing operation, substantially as shown.
